(57) **CLAIM**

We claim the ornamental design for an adapter plate for use in mounting an audio/visual device or the like to a surface, as shown and described.

DESCRIPTION

FIG. 1 is an isometric view of the claimed design.

FIG. 2 is a front elevational view of the claimed design of FIG.

1.

FIG. 3 is a rear elevational view of the claimed design of FIG. 1.

FIG. 4 is a top plan view of the claimed design of FIG. 1.

FIG. 5 is a bottom plan view of the claimed design of FIG. 1; and,

FIG. 6 is a left side elevational view of the claimed design of FIG. 1, the right side elevational view being a mirror image thereof.

The broken lines in the drawings are included for the purpose of illustrating subject matter that forms no part of the claimed design.

1 Claim, 5 Drawing Sheets
